UNITED STATES PATENT OFFICE.

REUBEN C. ELDIDGE, OF NIAGARA FALLS, CANADA, ASSIGNOR TO STANLEY WORKS, OF NEW BRITAIN, CONNECTICUT, A CORPORATION OF CONNECTICUT.

BACK-BAND BUCKLE.

No. 905,062.

Specification of Letters Patent.

Patented Nov. 24, 1908.

Application filed May 25, 1907. Serial No. 375,633.

To all whom it may concern:

Be it known that I, REUBEN C. ELDIDGE, a subject of Great Britain, residing at Niagara Falls, Canada, have invented certain 5 new and useful Improvements in Back-Band Buckles, of which the following is a full, clear, and exact description.

My invention relates to improvements in so-called back band buckles, the object being 10 to provide a superior construction in which the webbing is more securely held than heretofore, the construction, as a whole, being economically produced without sacrifice or waste of material.

15 In the drawings—Figure 1 is a plan view of the buckle as closed, ready for use; Fig. 2 is a side elevation thereof; Fig. 3 is a longitudinal section, the buckle being open; Fig. 4 is a transverse section adjacent the 20 plane of the buckle-gripping member.

1 represents the frame of the buckle which is of suitable contour and which has the slots 2—3.

4—5 are ears struck up from the frame at 25 points near the opposite edges thereof and between the passages 2—3.

6 is the clamping member pivoted at its opposite ends to the ears 4—5. This clamping member is out of action when standing, 30 as shown in Fig. 3, and in action when standing, as shown in Figs. 1, 2 and 4. The lower edge of the clamping member 6 is preferably serrated as at 6^a, while the free end is given a suitable turn, for example, the right-angle turn shown in the drawings, so that 35 when it is closed down, into its position of use (as shown in Fig. 2), it will close the passage into the hook 7, which latter depends from the frame 1.

40 8 is a flange struck up from frame 1 in forming the slot 2. This flange is turned back upon itself so as to form an abutment or shoulder of double thickness against which the webbing, when attached to the 45 buckle as in use, is forced by the clamping member 6^a. Directly under the edge of the clamping member 6^a are upwardly struck nibs or projections 9—9, which preferably alternate with the aforesaid serrations, as 50 best seen in Fig. 4. These nibs 9—9, the

serrations 6^a, and the abutment 8, all coact in securing a peculiarly effective grip on the webbing and prevent slippage.

The nibs 9—9 may be economically produced by simply indenting the body 1 at its 55 rear side so as to project or force the metal up on its opposite surface. By this arrangement all sharp teeth and points are avoided, which tend to cut or injuriously abrade the webbing. The method of leading the webbing through the buckle is indicated in Fig. 3, in which it is shown as leading into the opening 2 from the rear, thence under the clamping member, thence through the opening 3 to the rear of the body 1. 60

What I claim is:—

1. In a device of the character described, a buckle frame or body, ears struck up therefrom in the side of and near the edges thereof, said frame having two transverse passages or slots in the frame above and below said ears, the material of the body adjacent to one of said slots being folded back and down upon itself to form a raised shoulder on the upper face of said buckle frame, 70 raised nibs on the same surface of said buckle frame struck up from the metal of said frame and closely adjacent to said shoulder, and a hinged clamping member having a serrated edge, the serrations thereof 75 arranged to alternate with said struck-up nibs.

2. In a device of the character described, a buckle frame or body, ears struck up therefrom at opposite sides thereof and near the edges, but spaced apart therefrom, a series of struck-up nibs in the body of the buckle in line with and between said ears, a raised rib parallel with and above said nibs and formed by striking up and folding back a 85 portion of the metal of the buckle body along a line near, but away from the extreme upper edge thereof, a locking lever pivoted on said ears, a portion of said locking lever 90 co-operating with said nibs and rib.
